UNITED STATES PATENT OFFICE

ARLINE A. GRATZ AND ERICK J. AJAX, OF MINNEAPOLIS, MINNESOTA, ASSIGNEES TO
DOMINION ELECTRICAL MANUFACTURING CO., OF MINNEAPOLIS, MINNESOTA, A
CORPORATION OF MINNESOTA

DESIGN FOR A SADIRON

Application filed November 19, 1930. Serial No. 37,725. Term of patent 7 years.

To all whom it may concern:

Be it known, that we, ARLINE A. GRATZ and ERICK J. AJAX, citizens of the United States, residing at Minneapolis, in the county of Hennepin and State of Minnesota, have invented a new, original, and ornamental Design for a Sadiron, of which the following is a specification, reference being had to the accompanying drawing, forming part thereof, wherein:

Fig. 1 is a side elevation of a sadiron embodying our new design;

Fig. 2 is a plan view of the same, and
Fig. 3 is a front end elevation.

We claim:

The ornamental design for a sadiron, substantially as shown.

ARLINE A. GRATZ.
ERICK J. AJAX.
